UNITED STATES PATENT OFFICE.

GEORGE B. ROWE, OF OKLAHOMA, OKLAHOMA.

NEEDLE-THREADER.

1,117,522.

Specification of Letters Patent. Patented Nov. 17, 1914.

Application filed April 11, 1913. Serial No. 760,504.

To all whom it may concern:

Be it known that I, GEORGE B. ROWE, citizen of the United States, residing at Oklahoma city, in the county of Oklahoma and State of Oklahoma, have invented certain new and useful Improvements in Needle-Threaders, of which the following is a specification.

This invention relates to devices for threading needles, and has for one of its objects to improve the construction and increase the efficiency and utility of devices of this character.

Another object of the invention is to provide a simply constructed device whereby needles of various sizes and with eyes of various areas may be readily threaded in a dim light or in the dark or by blind persons.

With these and other objects in view the invention consists in certain novel features of construction as hereinafter shown and described and then specifically pointed out in the claim, and in the drawings illustrative of the preferred embodiment of the invention.

Figure 1 is a perspective view of the improved device from above. Fig. 2 is a perspective view of the improved device from beneath. Fig. 3 is a longitudinal sectional elevation of the improved device.

Corresponding and like parts are referred to in the following description and indicated in all the views of the drawings by the same reference characters.

The improved device comprises a stock 10 of any suitable material and of any suitable form, and preferably slightly less in length than the shortest needle through the eye of which it is designed to pass the thread.

The stock will preferably be formed with a flat upper side and a rounded lower side as represented, but it is not designed to limit the invention in any manner in this respect. Formed in the upper flat face of the body is a longitudinally extending groove or channel 11 opening at one end through the end of the stock and terminating at the other end a short distance from the adjacent end of the stock.

Depending from the stock at one end is a head or projection 12 having a converging aperture 13 with the smaller end of the aperture communicating with the groove 11 near its closed end as represented. The smaller end of the aperture is relatively small, and preferably of less diameter than

the eye of the smallest needle through which it is designed to pass the thread.

Extending from the stock 10 at one side is an arm 14, the upper face of the arm being in transverse alinement with the upper face of the stock. Riveted or otherwise attached at 15 to the arm 14 is a flat spring 16 which extends over the flat upper face of the stock and projects for a distance beyond the opposite edge of the same, as shown at 17, and is preferably slightly curved away from the stock to enable a needle to be more readily passed beneath the spring and into the groove.

To thread a needle by the improved device, the needle is forced beneath the holding spring 16 and into the groove 11 with the eye end against the closed end of the groove which position will place the eye of the needle in alinement with the reduced terminal of the aperture 13. If the eye of a needle is not in proper position it can be properly located by simply turning the needle either by thrusting a pin or the point of another needle in its eye and turning the latter until the eye is properly placed relative to the aperture. By this arrangement the converging aperture 13 forms a guide to the thread which may be thus thrust into the relatively large open end of the aperture and guided without special care through the eye of the needle. By this arrangement it will be obvious that it is only necessary to pass the thread into the relatively large open end of the aperture to cause the latter to be guided directly through the eye. The thread is then drawn through the eye of the needle for a distance and the needle extracted from beneath the spring and the surplus thread drawn through the aperture.

The improved device is simple in construction, can be inexpensively manufactured and adapted without structural change to needles of various sizes and lengths.

By this arrangement a person can thread a needle in a dim light, or when blind or partially blind, or whose eyesight is impaired, while at the same time the device is also very useful for persons with good eyesight to enable them to thread needles without special care or attention or straining the eyes.

Having thus described the invention, what is claimed as new is:

A device of the character described in-

cluding a stock provided with a flat face and having a longitudinally extending groove formed therein, the stock being formed with a depending head having a longitudinally directed opening formed therein communicating with said groove, the walls of said opening converging toward the groove, said stock also having a laterally extending arm formed thereon provided

10 with a flat face in transverse alinement with the flat face of the stock, and a flat spring carried by the arm and extending transversely of the face of the stock and across

said groove, said spring normally bearing against the flat face of the stock and being bowed upwardly adjacent its free extremity away from said face, whereby a needle may be readily passed between the adjacent extremity of the spring and the contiguous flat face of the stock for insertion in said groove. 20

In testimony whereof I affix my signature in presence of two witnesses.

GEORGE B. ROWE. [L. S.]
